EYEGLASSES OR THE LIKE

Allen Lee, 1416 Reistertown Road,
Pikesville, Md. 21208

Filed Aug. 5, 1970, Ser. No. 24,328

Term of patent 14 years

Int. Cl. D16—06

U.S. Cl. D57—1

FIG. 1

FIG. 2

FIG. 1 is a perspective view of eyeglasses or the like showing my new design;

FIG. 2 is a top plan view thereof.

The rear of the eyeglass frame is flat and unornamented.

The eyeglass frame is stipple shaded to indicate contrast.

I claim:

The ornamental design for eyeglasses or the like, as shown and described.
